(57) **CLAIM**

The ornamental design for a multi-slot sheet feeder, as shown and described.

DESCRIPTION

FIG. 1 is a perspective view of a multi-slot sheet feeder in accordance with our new design, shown in use on a sheet scanner;

FIG. 2 is a second perspective view thereof, shown at an enlarged scale;

FIG. 3 is a front elevational view thereof;

FIG. 4 is a rear elevational view thereof;

FIG. 5 is a top plan view thereof;

FIG. 6 is a bottom plan view thereof;

FIG. 7 is a left side elevational view thereof, shown at an enlarged scale; and,

FIG. 8 is a right side elevational view thereof, shown at an enlarged scale.

The broken lines in FIGS. 1-8 depict environmental subject matter only and form no part of the claimed design.
